DENTAL PRESS

James C. Sharrock, Birmingham, Ala., and
John A. Sheeley, Stamford, Conn.

Application May 3, 1946, Serial No. 666,862

3 Claims. (Cl. 18—5.7)

1

Our present invention relates to an improvement in presses and more particularly to a press which is especially adapted for use in dental laboratories in the molding of dentures, and has for an object the provision of a press of the character designated which shall be simple and sturdy of design, reliable in operation, and readily adjustable for use with various materials and types of molding flasks.

Another object of our invention is to provide a dental press which embodies a pressure regulating valve and a manually operable three-way valve in series therewith, whereby the pressure at which the press is to be operated may be set and the platens operated merely by opening the manually operable valve.

A further object of our invention is to provide a dental press embodying an air cylinder which is connected with a movable platen through a compound linkage so designed as to increase, in compact space, the pressure applied to the platen over that exerted by the piston, and at the same time provide adequate stroke for the piston.

A further object of our invention is to provide a press of the character described embodying an adjustable platen which is so supported with respect to the other platen that it has limited pivotal movement, thereby to accommodate itself to the unevenness of the flask being pressed between the two platens.

As is well known in the art to which our invention relates, in forming dentures from the various moldable products employed therefor, rather high pressures are required which vary with different materials.

Presses as heretofore known to us have had their platens fixed with respect to their mountings so that if a flask was placed therebetween, uneven stresses were set up in the flask, the platens themselves, and the supporting frame work therefor. Accordingly, it is an object of our invention to overcome these difficulties, to provide for the application of any required pressure, and to compound the motion between the cylinder and the movable platens within a compact space, thereby to permit the use of lower operating pressures within the cylinder and to provide for adequate movement of the movable platen.

Apparatus embodying features of our invention is illustrated in the accompanying drawing, forming a part of this application, in which

Fig. 1 is a side elevational view of our improved press with certain parts broken away and in section;

Fig. 2 is a bottom plan view; and

2

Fig. 3 is a detail sectional view taken along the line III—III of Fig. 1.

Referring now to the drawing for a better understanding of our invention our improved press comprises a base 10, which may be open at the bottom to permit servicing the working parts and a top plate 11.

10 Mounted on the plate 11 by means of studs 12 is an air cylinder 13 embodying the usual piston 14, and piston rod 16. The cylinder 13 is provided with a head 15 having a socket 17 through which the piston rod 16 passes. A spring 18 surrounds the piston rod 16 and extends up into the socket 17, bearing against the upper end thereof, thereby to return the piston to the bottom of the cylinder 13 when pressure is relieved as will be later explained.

20 Pivotedly connected at 21 to the upper end of the piston rod 16 is a lever 22 which is fulcrumed at 23 to a link 24, pivoted in turn, at 27, to brackets 26, fast on the cylinder 13. At its other end, the lever 22 is pivotedly connected at 28 to a link 29 which passes through an enlarged opening 31 in the plate 11, and is pivotedly connected at 25 its lower end beneath the plate 11 to a floating lever 32. The lever 32 passes through a pair of brackets 33 and 34, and is pivotedly connected as at 36 to a vertically extending pin 37. A small roller 38, journaled in the brackets 33 on a shaft 39, acts as a fulcrum for the lever 32 when pressure is applied. The lower or movable platen 41 is carried on the upper end of the pin 37, the pin being held vertical by passing through a guide block 42 secured to the under side of the top plate 11.

30 Secured to the top of the plate 11 are a pair of vertically extending rods 43 which are connected at their upper ends by a plate 44. Threaded through the center of the plate 44 is an adjusting bolt 46 which carries a locking nut 47.

40 The lower end of the bolt 46 is rounded as shown at 48 and fits within a spherical seat 49 formed in an upper platen 51. A small pin 52 passes through a boss 53 formed on the platen 51 thereby to prevent the platen from falling off the end of the adjusting bolt 46.

45 The control means for the air cylinder comprises a pressure regulating valve 54 to which air under pressure is supplied through a pipe 55 from a suitable source, not shown. The pressure regulating valve 54 is provided with an adjusting wheel 57 which may be located on the outside of the machine, whereby the operating pressure of the cylinder may be adjusted or changed 50 as required. Air under pressure from the pres-

sure regulating valve is passed through a pipe 58 to a manually operated three way valve 59, having one outlet 60 thereof in communication with the lower end of the cylinder 13. The exhaust outlet of the valve 59 is indicated at 61.

To the operating connection 62 of the valve 59 is secured an operating rod 63 which projects from the front of the press and is provided with an operating handle 64.

From the foregoing the operation of our improved press will be readily understood. The pressure at which the cylinder is to be operated is fixed by setting the pressure regulating valve 54, the pressure being indicated by a gauge 55. It is only necessary for an operator to open the three way valve 59 by rotating the handle 64 to the proper position, whereupon air under pressure is admitted beneath the piston 14 causing the piston to actuate the levers and raise the movable platen 41. Conversely, when it is desired to separate the platens, pressure is released by rotating the handle 64 to the exhaust position of valve 59, whereupon spring 18 causes the piston 14 to move downwardly.

It will be noted that the suspension point for the roller 38 is closer to the pivot point 36 than to the other pivoted end of the cross link 32, thus resulting in again compounding the motion in the linkage. In actual operation, a six inch diameter cylinder operating at 60 lb. pressure develops approximately 8,000 lbs. pressure between the platens 41 and 51, the motion being compounded in the ratio of about 5 to 1.

From the foregoing it will be apparent that we have devised an improved dental press which is simple and sturdy of design and economical of manufacture, and one in which the valve arrangement permits the pressure applied to the work to be varied by a simple adjustment.

While we have shown our invention in but one form, it will be obvious to those skilled in the art that it is not so limited, but is susceptible of various changes and modifications, without departing from the spirit thereof, and we desire, therefore, that only such limitations shall be placed thereupon as are specifically set forth in the appended claims.

What we claim is:

1. In a dental press, a base, an air cylinder mounted on the base, a piston and rod within the cylinder, a pressure regulating valve, a manually operable three-way valve interposed between the cylinder and the pressure regulating valve, a vertically movable platen, compound linkage connecting the piston rod and the movable platen, a pair of vertically extending rods secured to the base, a connecting plate at the top of the rods passing over the center of the

movable platen, a bolt threaded through the plate and in vertical alignment with the center of the movable platen, the lower end of said bolt being spherical, a fixed platen having a spherical seat to receive the spherical end of the bolt, and a pin loosely connecting the platen to the bolt.

2. In a dental press, a base, an air cylinder mounted on the base, a piston and rod within the cylinder, a pressure regulating valve, a manually operable three way valve interposed between the pressure regulating valve and the cylinder, a vertically movable pin projecting upwardly through the base, a lower platen fast on the upper end of said pin, compound linkage connecting the piston rod to said pin comprising upper and lower levers and links, a roller providing a fulcrum for the lower lever, a pair of vertically extending rods secured to the base, a connecting plate at the top of the rods passing over the center of the platen, a bolt threaded through the plate and in vertical alignment with the center of the platen, the lower end of the bolt being spherical, a fixed upper platen having a spherical seat to receive the spherical end of the bolt, and a pin loosely connecting the fixed platen to the spherical end of the bolt.

3. In a press, a pressure cylinder, a piston rod within the cylinder, a movable platen, an upper lever pivotally connected at one end to the piston rod, a vertically depending link connected to the other end of the upper lever, a second link connected at one end to the cylinder and at the other end to the upper lever intermediate the ends thereof, a lower lever pivotally connected at one end to the lower end of the vertically depending link, a vertically extending pin connected at its upper end to the movable platen and at its lower end to the lower lever, a roller beneath the lower lever providing an antifriction fulcrum therefor, a fixed platen, and means to adjustably support the fixed platen comprising a threaded bolt having a spherical end, a spherical seat on the platen adapted to receive the spherical end of the bolt, and a pin loosely connecting the platen and bolt.
